UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

SPARK-PRODUCING MECHANISM.

Application filed February 8, 1922. Serial No. 535,022.

To all whom it may concern:

Be it known that I, WILLIAM J. FRISBIE, a citizen of the United States, and a resident of Chicago, in the county of Cook and State of Illinois, have invented certain new and useful Improvements in Spark-Producing Mechanism, of which the following is a specification.

My invention relates to spark producing mechanism which is particularly useful as an attachment on the reflectors of miners' acetylene lamps and is of the type in which a serrated friction wheel cooperates with pyrophoric material to produce ignition sparks, a lever being provided for conveniently rotating the wheel to wind up a spring which when released will rapidly rotate the wheel in association with pyrophoric material to produce a stream of sparks which are directed to the gas outlet of the lamp with which the attachment is associated. The wheel supporting mechanism is secured to the reflector near the outer edge thereof and the lever is attached to be swung in a diametral plane including the gas outlet so that the produced sparks will be thrown toward the tip to ignite the issuing gas. The main object of my invention is to so construct the lever that when it is rotated into position in front of the gas outlet to wind up the spring it will form a channel from the outlet to the wheel which channel serves to collect issuing gas and conduct it in a stream between the outlet and wheel to be ignited by the sparks produced when the lever is released. This will assure the ignition of the lamp in wind or drafts or when the pressure in the lamp is low and only a limited amount of gas issues from the burner.

My improved construction is clearly illustrated on the accompanying drawing on which—

Fig. 1 is a front elevational view of a miner's cap lamp with part of the reflector broken away and the sparking attachment applied thereto,

Fig. 2 is an enlarged sectional view on plane 2—2 Fig. 1 showing the lever swung inwardly,

Fig. 3 is a sectional view on plane 3—3 Fig. 1,

Fig. 4 is an enlarged sectional view on plane 4—4 Fig. 1.

The lamp to which I have shown my attachment applied is a miner's cap lamp com-

prising the water container A, the carbide cup B, the gas tube C, and the reflector D, the valve lever E controlling the flow of water to the carbide for the generation of acetylene gas.

The sparking device comprises a frame having the base 10 from which extends the threaded sleeve or barrel 11 for receiving the block of pyrophoric material 12 and the spring 13, the cap 14 having threaded engagement with the outside of the sleeve for controlling the compression of the spring and its pressure against the pyrophoric material. Extending upwardly from the base 10 are the two parallel walls 15 and 16 which at their outer ends support the pivot pin or axle 17 which as shown, may be in the form of a tube. A serrated friction wheel 18 has the central opening 19, and secured to this wheel as by rivets 20 is the lever frame 21 formed of sheet metal, this frame having the opening 22 registering with the opening 19 of the friction wheel. The openings receive the pivot pin 17, and surrounding this pin is the coiled spring 23 which has its one end 24 secured to the lever and its other end 25 anchored to the wall 15. The diameter of the openings 19 and 22 is sufficient to readily receive the coiled spring and to permit the spring to readily expand after having been contracted.

When the device is applied to the lamp sleeve 11 is inserted through the hole 26 in the reflector, the reflector being then clamped between the base 10 and the nut 27 engaging the threaded sleeve. The attachment is positioned with the friction wheel in a diametral plane including the gas orifice of the tube C. The arrangement of the spring is such that the lever will normally be held outwardly with its end against the reflector edge. The pyrophoric material 12 is held against the friction wheel by the spring 13 and when the miner desires to light the lamp he swings the lever in-

wardly toward the gas tube and then releases it. Swing of the lever causes the spring 23 to be wound up so that upon release it will rapidly rotate the lever and friction wheel, the engagement of the sharp points on the wheel with the pyrophoric material then causing the production of

sparks which are directed in a stream toward and across the gas outlet of the tube C, the issuing gas being then ignited.

Frequently the lamp is used where there is a draught or wind, and sometimes the sparking is weak or the pressure in the gas chamber of the lamp is low. The important 5 object of this invention is to so construct the lever 21 that it will serve, when swung inwardly, to provide a passageway or channel from the gas orifice to the friction wheel whereby gas will be collected and conducted 10 in a stream toward the friction wheel to be ignited by the sparks produced. I therefore make the lever structure of substantially U-shaped cross sections, the walls 28 and 29 with the base 30 then forming a 15 channel P between the gas tip and the friction wheel when the lever is swung inwardly as shown in Fig. 2. The end of the lever is widened out to form a cap 31 which will engage over the end 20 of the gas tip when the lever is swung in, such application of the cap more or less restricting the outflow of the gas so that it will acquire some pressure particularly when the pressure in the carbide cup is 25 low normal. The issuing gas will enter the channel formed by the lever and will travel towards the friction wheel and will be fully protected against draught. Then when the lever is released and is suddenly thrown back 30 by its spring the produced sparks will ignite the gas stream and the flame will be communicated to the tip. Ignition of the lamp is thus assured even though the sparking may be weak, or the gas pressure low.

35 The wall 29 of the lever is wider than the wall 28 so that the slot 32 may be provided for accommodating the end 24 of the lever actuating spring, this end being looped around the edge of the wall 29 as clearly 40 shown in Fig. 2.

The lever is normally held out against the edge of the reflector as indicated in Figs. 1 and 3, and the smooth rounded back of the cap end 31 will offer a convenient means for 45 engaging the lever with the finger so that it may be readily swung inwardly and then released.

Having described my invention I claim as follows:

50 1. The combination of a gas outlet, a frame supported adjacent to said outlet and having a bore, a friction wheel pivoted on said frame in a plane including said gas outlet, pyrophoric material in said bore for 55 cooperating with said wheel, a lever pivoted on said frame and adapted to be swung toward and away from said outlet, said lever having a channel for receiving gas from said outlet and conducting it towards said wheel, means resisting swing of said lever towards said outlet and tending to return it when released, and means connecting said 60 wheel with said lever whereby said wheel is rotated during return of the lever to cooperate with the pyrophoric material to produce 65

sparks for igniting the gas conducted toward the wheel by said channel.

2. The combination with a gas outlet, of a frame supported adjacent thereto, a friction wheel pivoted on said frame in a plane 70 including said outlet, pyrophoric material and means for holding it for cooperating with said wheel, a lever pivoted on said frame concentric with said wheel to be swung toward and away from said outlet, 75 said lever presenting a guideway for the flow of gas from said outlet towards said wheel when said lever is swung to said outlet, means for resisting swing of said lever towards said outlet and for returning it 80 when released, and means for causing rotation of said wheel during return movement of said lever whereby sparks will be generated to ignite the gas guided towards said wheel by said lever. 85

3. The combination of a gas outlet and spark producing mechanism, said mechanism comprising a frame supported adjacent to said outlet, a spark wheel pivoted on said frame to rotate in a plane including said 90 outlet, a lever pivoted adjacent to said wheel and adapted to be swung toward and away from said outlet, said lever having a passageway for conducting gas from said outlet towards said wheel when said lever is swung 95 to said outlet, pyrophoric material for cooperating with said wheel, and means for rotating said wheel when said lever is swung away from said outlet, whereby sparks are produced and the gas ignited. 100

4. The combination with a gas tip having a gas orifice, of spark producing mechanism, said mechanism comprising a frame supported adjacent to said tip, a friction wheel pivoted on said frame, a lever pivoted on 105 said frame adjacent to said wheel to be swung toward and away from said orifice, a spring tending to hold said lever away from said orifice, said lever having a passageway for receiving gas from the outlet 110 and conducting it towards the wheel when the lever is swung in front of the orifice, pyrophoric material, and means for causing said wheel and pyrophoric material to cooperate when said lever is swung back by the 115 spring whereby sparks are produced to ignite the gas. 120

5. The combination with a gas tip having a gas passageway therethrough, of spark producing mechanism, said mechanism comprising a frame supported adjacent to the tip outlet, a friction wheel pivoted on said frame to rotate in a plane including said outlet, a lever pivoted on said frame adjacent to said wheel to swing in a plane parallel 125 to that of the wheel, a spring tending to hold said lever away from said tip, the end of said lever forming a cap for engaging in front of the tip outlet when the lever is 130 swung towards the tip whereby the outflow

of gas is restricted, and pyrophoric material cooperating with said wheel during return movement of said lever to produce sparks for igniting the released and issuing gas.

5 6. In a gas lamp, the combination of a burner tip, a reflector surrounding said tip, spark producing mechanism comprising a frame mounted on said reflector, a friction wheel pivoted on said frame to rotate in the 10 plane of the gas passageway through said tip, a lever pivoted on said frame to swing parallel with said wheel, a spring tending to swing and hold said lever outwardly away from the tip, said lever when swung inwardly bridging the space between said 15 wheel and the tip and affording a passageway for receiving and conducting gas toward the wheel, means for rotating said wheel when the lever is returned by its 20 spring, and pyrophoric material cooperating with the wheel to produce sparks for igniting the conducted gas.

7. In a gas lamp, the combination of a reflector, a burner tip arranged in the axis of 25 the said reflector, spark producing mechanism comprising a frame secured on the reflector a distance away from the burner tip, a friction wheel pivoted on said frame, a lever pivoted on said frame to swing in a 30 diametral frame toward and away from said tip, a spring resisting inward spring of the lever and tending to return it to an outer position away from the tip, said lever when swung inwardly presenting its end in front

of the tip outlet to receive the flow of gas 35 therefrom, walls on said lever forming a passageway for conducting gas away from the tip towards the wheel, means for rotating said wheel when the lever is returned to its outer position, and pyrophoric material 40 cooperating with the wheel to produce sparks to ignite the conducted gas.

8. In a gas lamp, the combination of a reflector, a burner tip positioned in the axis of said reflector, spark producing mechanism comprising a frame secured on said reflector a distance outwardly from said tip, a friction wheel pivoted on said frame, a lever pivoted on said frame to swing in a diametral plane toward and away from said 45 tip, a spring tending to resist inward swing of said lever and to return it to an outer position after such inward swing, the end of said lever being shaped to form a cap to be positioned in front of the tip when said lever is swung inwardly whereby the flow of gas 50 will be deflected, walls on said lever forming a passageway between the tip and wheel for conducting gas toward the wheel, means for rotating said wheel during return movement 55 of said lever, and pyrophoric material for cooperating with the wheel to produce sparks for igniting the conducted gas.

In witness whereof, I hereunto subscribe my name this 3rd day of February A. D., 60 1922.

WILLIAM J. FRISBIE.
